United States Patent

Des. 242,371
Patented Nov. 16, 1976

242,371

GAME BOARD

Edward Maurice Gold, Regent Bldg., Corner of Manners
& Lombard Sts., Wellington, New Zealand

Filed Oct. 11, 1974, Ser. No. 514,321

Term of patent 14 years

Int. Cl. D21—01

U.S. Cl. D34—5 SS

The figure is a top plan view of a game board showing my new design. The board is of conventional thickness.

I claim:

The ornamental design for a game board, substantially as shown and described.
